(Cl. D74—1)

To all whom it may concern:

Be it known that I, Herbert W. Marano, a citizen of the United States and a resident of Brooklyn, New York, have invented a new, original, and ornamental Design for a Staple Remover or Similar Article, of which the following is a specification, reference being had to the accompanying drawing, forming a part hereof, in which

Figure 1 is a side elevational view of a staple remover or similar article, showing my new design;

and

Figure 4 is a rear elevational view thereof.

I claim:

The ornamental design for a staple remover or similar article, as shown.

HERBERT W. MARANO.
